UNITED STATES PATENT OFFICE.

JOHN W. STEINMEYER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

GRAIN-HOPPER.

1,109,601.

Specification of Letters Patent.

Patented Sept. 1, 1914.

Application filed December 17, 1912. Serial No. 737,236.

To all whom it may concern:

Be it known that I, JOHN W. STEINMEYER, residing at St. Louis, Missouri, and being a citizen of the United States, have invented certain new and useful Improvements in Grain-Hoppers, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a horizontal sectional view taken through one side of a car adjacent the door and just above the plane of the floor at the side door, and showing in plan one-half of the door in horizontal position as part of the flooring and the other half in vertical door-closing position so as to disclose the inside of the hopper. Fig. 2 is a fragmentary side elevation of the device disclosed in Fig. 1, parts broken away to show internal construction of the hopper on the far side of the center sills. Fig. 3 is a vertical transverse sectional view taken through the hopper and floor with the hopper door shown in solid lines in locked position and in dotted lines in unlocked position, and taken on a plane indicated by the line 3—3 of Fig. 2, looking in the direction of the arrows. Fig. 4 is a transverse vertical sectional view taken at one end of the hopper and showing a portion of the same in side elevation and the hopper door in open position, and taken on the plane indicated by the line 4—4 of Fig. 2, looking in the direction of the arrow. Fig. 5 is a fragmentary elevation, showing the upper left hand portion of the side grain door illustrated at the left in Fig. 2, an adjacent portion of the side wall, and a lock for said door. Fig. 6 is a horizontal sectional view of the parts shown in Fig. 5, and taken on a plane indicated by the line 6—6 of Fig. 5. Fig. 7 is a vertical longitudinal sectional view through one of the intermediate stringers, and taken on the plane indicated by the line 7—7 of Fig. 4.

My invention relates in general to the hopper bottom of a grain car, and specifically relates to a combined grain door and hopper cover, and also relates to a means for closing and locking the hopper door.

It is an object of my invention to provide a side door for a grain car, which door may be lowered into horizontal position to cover one of two transversely disposed hoppers when it is desired to use the car as a box car.

Another object of my invention is to provide a novel construction of hopper which is securely braced in position on the underframe, and in which the underframe is constructed to attain the maximum bracing effect in a car of this construction with the least amount of structural parts or elements.

It is a further object of my invention to provide a hopper, the drop door of which is held in locked position by the weight of the door and a distributed lading, but which may be released and swung to open position by a concentration of the weight of the lading.

I attain the above outlined objects, broadly, by positioning transversely of and in juxtaposition to the side doors of the car a pair of hoppers, which hoppers are preferably constructed of a single sheet of metal, bent into hopper shape and securely braced to the underframe elements. Adapted to extend transversely of and supported by the side and center sills is a pair of grain supporting doors, which when used to support grain are placed in horizontal position but which may be swung into vertical position to partially close the side doors, thereby uncovering the hoppers. The lower edge of the hopper opening has an upturned flange adapted to support the lower side of a hinged drop door, which door is adapted to be lifted bodily by a toggle link to clear the flange so that the lading and weight of the door will act to swing the same into open position.

My invention relates to other elements and combination of elements and parts arranged to attain a well braced and readily constructed combined grain and box car, all as more fully hereinafter described and claimed.

While I have shown as a vehicle for my invention a conventional form of car, it

is, of course, to be understood that the invention is not specifically limited to this form of car but may be adapted to other forms with obvious mechanical modifications and adaptations, and in the illustration but one hopper and its adjacent elements will be described in detail, it being understood that the similar elements are disposed in the corresponding position on 10 the opposite side of the center sill.

Described more in detail I have shown one of a pair of channel-shaped center sills A, which pair is connected by a center sill cover plate B, and spaced from which center 15 sill is a conventional form of flanged or channel shaped side sill C. It will be noted that, as is usual with constructions of this character, the center sill is relatively deeper than the side sill, but in this particular instance the top of the side sill is positioned slightly higher than the top of the center sill, so that the grain door hereinafter described will be flush with the permanent car 20 floor D when said grain door E is in its lowered position. When in its raised position it will be understood that the door fits between the door posts F, which, together with the furring pieces G, form an outline for the grain door and constitute part of the 25 side wall H.

A conventional cross-bearer J extends transversely of the car at each door post, between which cross-bearers and between the side sill and the adjacent center sill element 30 is disposed the hopper K, particularly forming a part of the subject-matter of this invention.

Paralleling the center and side sills and positioned substantially midway between 40 the same and passing through the sides of the hopper K, in a manner more particularly hereinafter described, and overlapping the cross-bearer is a longitudinally extending intermediate stringer L, Z-shape in cross 45 section, the upper flange of which is nearly flush with the top of the side sill C. Suitably riveted to the front face of the side sill and adjacent at the top thereof is an inverted reinforced L-shaped threshold plate M, 50 which projects above the side sill a distance equal to the thickness of the door E, so that the top of the door E, when used as a part of the floor, will be flush with the top of the threshold plate, as shown in Fig. 3.

The door E comprises a series of wooden 55 pieces 8, fastened together and reinforced by an intermediate wooden batten 9, bolted to the under or rear side of the door, each longitudinal edge of the door being bound 60 by a metallic L-shaped batten 10 the upper or inner batten 10 having a filler 11 disposed between one flange thereof and the door, so as to form with the batten 10 a projecting flange or stop which, when this part of the 65 door is resting on the center sill cover plate

B, will contact with the retaining piece 12 to prevent transverse movement of the door in one direction, the corresponding door on the opposite transverse side preventing movement in the other direction.

As the center sill is positioned below the plane of the car floor D a distance equal to the thickness of the retaining piece 12, and as the side sill is raised above the center sill this distance, the effect will be that the 70 door E when used as a part of the flooring will be in a substantially horizontal plane with one side of the door fitting in the angle between the threshold plate and the top of the side sill, resting on the side sill when in 75 the raised position shown in Fig. 4, or, the lowered position shown in Fig. 3. The inner side of the door is, of course, supported by the center sills and center sill cover plate, and is supported intermediate its width by 80 the intermediate stringer L. Each transverse edge of the door is bound by a Z-shaped 85 outstanding flanged plate 13 inset into the door, the projecting flange of which, as shown more particularly in cross section in 90 Fig. 2, fits into a pocket or groove in the adjacent flooring D.

When in its raised position, the door fits within the door opening and flanged plate 13 fits within a recess in the rear of the 95 furring piece G, and is locked in position by means of the gravity latch N (Figs. 5 and 6) carried by the door post. In order to prevent surreptitious removal of the door from the car, the door is attached to the side sill 100 by some flexible connection, such as the short length of chain P.

Referring to the hopper K, it will be noted that the body thereof is formed of a single sheet of metal bent into a three-sided hopper form, with an opening to the longitudinal side of the car below the door opening in the body portion of the car. The rear wall 14 of the hopper has its upper end bent 105 horizontally to form an attaching flange 15, positioned between the top of the adjacent center sill element A, and the center sill cover plate B, and fastened to these members by means of rivets 16. This inside wall of the hopper is braced from the lower portion 110 of the center sill by means of the angle bracket 7, having one end fastened to the lower flange of the center sill element and the other end upwardly angled to fit the inclined hopper wall.

Extending transversely of the car and adjacent each of the cross-bearers J, and positioned between the cross-bearer and the adjacent side plate 17 of the hopper K, are short transverse pieces 18 intermitted so as 115 to permit the intermediate stringer L to pass therethrough. The outside end of the pieces 18 is inset in pockets 21 in the filler block 22, carried between the flanges of the side sill C, the end of the transverse piece fitting 120 130

the upper portion of the channel and conforming in configuration to the underside of the upper flange of the side sill.

Each transverse side 17 of the hopper has its upper end bent outward to form a flange 23, which overlaps the transverse pieces 18 and is bolted or otherwise fastened to these pieces as shown in Figs. 2, 4 and 7. The upper part of each side sheet 17, at its outer edge, is bent at right angles to said sheet to form a flange 24. These flanges parallel the side sills and are bolted to filler blocks 22, which are carried in the concavity on the inner side of the side sills.

15 From this construction it will be seen that the side sill itself forms the upper front portion of the hopper, and the hopper opening extends substantially from the bottom of the side sill to adjacent the bottom of the 20 inside or rear wall 14. This inside or rear wall has an upturned flange 25 formed integral with a reduced extension 46 of the front flanges 24 adapted to support the door, as hereinafter described.

25 To brace the transverse sides 17 of the hopper above the door opening, to form a guide for the upper edge of the door and to form a chute for the lading in the vicinity of the channel of the side sill, there is positioned within the hopper a downwardly and inwardly inclined hood plate 27, each longitudinal end of which has an upturned flange 28 fastened to the side of the hopper, the upper edge of the plate 27 being bent 35 outwardly to fit beneath the lower flange of the side sill C, to which it is fastened by any suitable means, such as the rivets adapted to hold the door bracket, hereinafter described.

40 In order to close the portion of the sides of the hopper which were cut away in order to insert the Z-shaped stringer L, there is disposed between each of the angles of the stringer a wooden filler 29 having an inclined face 30 (see Fig. 7) adapted to conform to the inclination of the side 17 of the hopper. The portion of the side cut away to accommodate the stringer is bent to form an underlapping lip or flange 31 fastened to 50 the underside of the transverse pieces 18, assisting to hold the two parts thereof in position.

The hopper door Q is of a trapezoidal form and preferably formed of a flanged plate, which door when in closed position rests within the upturned flanges 25 and 46, and is then positioned to the outer and underside of the hood plate 27 and positioned a distance from the side sill and its attached 55 parts sufficient to permit the door to slide in its own plane a distance at least sufficient to uncover the flanges 25 and 46, as shown in dotted line construction in Fig. 3.

The door is hinged to the side sills preferably by means of a pair of slotted hinges 33.

The slot being in a plane parallel to the plane of the door permits the sliding movement hereinbefore referred to. In order to actuate the door both to slide the same and to swing the same positively into its open position shown in Fig. 4, or into the closed position shown in Fig. 3, there is affixed to the side sill and to the underside of the outstanding flange of the hood plate 27, a centrally disposed bracket 34 carrying a pivot pin 35, to which is pivoted in turn the upper end of a pair of depending, freely swinging links 36, the lower end of which links are in turn pivoted by means of the pin 37, which constitutes the fulcrum for an actuating lever 38, one arm of which lever constitutes a bent handle 39 extending to the outside of the side sill in all the positions of the door, the other end of which lever is pivoted by means of the pin 40 to the bracket 41, mounted centrally upon the under or outer face of the door Q.

Noting Fig. 4 it will be seen that actuating the handle 39 will swing the door on its hinge 33 into position to close the hopper outlet, the arrangement of the links being such that the door is permitted to swing into the hopper until this upper portion contacts with the hood plate 27. Then with the pivot pin 37 as a relatively stationary pivot, the handle 39 is raised from the dot and dash position shown in Fig. 3 into the full line position shown in this figure, which has the effect of lowering the door from its dotted position shown in this figure into its full line locked position. The handle is then locked in position by some suitable form of catch, lock or hasp passing through co-acting apertures in the handle and an extension 47 from the bracket 34.

By this construction it will be seen that the weight of the lading carried by the door is supported by the flange 25 of the hopper itself and the weight of the lading is also transmitted through the links and parallel lever 38, so that there is but little tendency for the door to open due to the weight of any lading above it, and at the same time there is afforded a means for readily moving the door into unlocked position so that the weight of the lading will tend to open the same, but in case of an ice seal the long handle will afford a material leverage to positively open the door.

What I claim is:

1. In a car, the combination with a center sill having a retaining strip thereon, of a side sill having a threshold plate extending above said side sill, a removable floor adapted to rest on said retaining strip and side sill, and having a portion adapted to engage the strip on the side opposite the side sill, one side of said door abutting said threshold plate.
2. The combination with a center sill, of

105

110

115

120

125

130

- a side sill having its upper face disposed above the plane of the upper face of the center sill, and a door adapted in one position to be restrained from movement transversely of the sills by an opposing door and to be supported by said sills, the upper surface of said door being in a plane above both said center and side sills.
3. In a car, a hopper, center and side sills, intermediate longitudinal stringers disposed between the center and side sills and threaded through the sides of said hopper, transverse hopper-supporting members, each lapped by one of said intermediate stringers.
4. In a car, cross-bearers, transverse pieces in juxtaposition to and paralleling said bearers, and a hopper having outturned flanges supported by said pieces.
5. In a car, cross-bearers, transverse pieces in juxtaposition thereto, center sill and side sill, a hopper having outturned flanges overlapping said center sill and transverse pieces, and means attaching said hopper to said side sill.
6. In a grain car, a hopper bottom and a car side having a door opening in juxtaposition to the top of said hopper bottom, and a grain door adapted to be locked in movement-restraining position substantially within the door opening to partly close said side door opening, or to cover said hopper bottom, and to be maintained in such latter position by space restrictions.
7. In a car having a side door opening, a side sill, a threshold plate projecting above said sill across said door opening, and a door adapted when in a closing position to
- abut a vertical wall of said plate, and when in position as part of the car floor to have its upper face flush with the top of said plate.
8. A car having transversely disposed side door openings, threshold plates, side sills positioned below the upper surface thereof, center sills, a hopper disposed between each side sill and the center sill, a pair of door elements, one for each door opening, each adapted in one position to rest upon one of said side sills and against a vertical wall of a threshold plate to partially close one of said door openings, and when in position resting on the sills co-acting to form a portion of the car floor, and adapted to restrain each other from movement transversely of said sills.
9. A car having transversely disposed side door openings, a hopper disposed between each side sill and the center sill, a pair of door elements, one for each door opening and each adapted in one position to be supported upon a side sill to close one of said door openings, and when in position resting on the sills co-acting to form a portion of the car flooring covering said hoppers, and intermediate stringers adapted to sustain hopper-supporting elements and to afford additional support for said door elements.
- In witness whereof I have hereunto set my hand in the presence of two witnesses.

JOHN W. STEINMEYER
